HYDRAULIC ELEVATOR.

1,159,038.

Specification of Letters Patent.

Patented Nov. 2, 1915.

Application filed February 18, 1907. Serial No. 357,858.

To all whom it may concern:

Be it known that I, KARL E. OSSIAN JANSSON, a citizen of the United States, residing at Flushing, in the county of Queens and 5 State of New York, have invented certain new and useful Improvements in Hydraulic Elevators, of which the following is a full, clear, and exact specification.

This invention relates to hydraulic elevators and has particular reference to improvements in elevator systems of the hydraulic plunger type whereby power may be economized, the rise and speed of operation increased, as well as greater facility of 15 control and safety secured.

In the plunger elevator systems in common use, the car is usually underbalanced by the counterweight to a considerable degree, this difference being what is known as "dead load", as distinguished from the passengers and goods carried, known as "live load". In raising this dead load, power is necessarily wasted, and it has been impracticable to reduce this loss by close counterbalancing, by 25 reason of the tendency of the main plunger at high speeds, to bottom off the water, when the flow is suddenly cut off. At the present time this tendency is overcome in part by means of this unbalanced load.

According to this invention, an approximately balanced system is provided, having preferably the greater weight on the counterbalance side, and to enable the car to be accurately controlled without bounding, 30 means is provided for applying hydraulic power to the counterweight when the car is to descend, whereby the car becomes temporarily unbalanced, so that it will descend by gravity upon a proper manipulation of the main valve. To cause the car to ascend, power is applied to the main plunger and a valve operated to permit descent of the counterweight at the same time means being provided in stopping to temporarily remove 35 the pull of the counterbalance, so that the car stops by its own weight without bounding. To accomplish this, a special form of three-position valve is provided for simultaneously controlling both the main plunger 40 cylinder and the counterweight cylinder. It 45 will be understood, that the function of this

valve broadly is to simultaneously control both cylinders, in such manner as to permit one plunger to ascend and the other to descend, which result may be accomplished 55 in various ways, though I consider the valve herein described of particular advantage for this purpose.

As herein shown, the counterweight cylinder is disposed above the main cylinder and the head of water therein is utilized to raise the car, while the car is lowered by admitting pressure under the counterweight and opening the main cylinder to exhaust.

The advantages of such a system are 65 numerous, among which may be mentioned, that the power consumed will be very materially less; the stresses in the parts being distributed, will not require such heavy construction; the system will be under close control and can therefore be operated at high speeds much quicker than is now practicable; both sides being supported by water, there will be no danger of falling or of sudden ascent; and the rise can be increased 70 over what is now practicable without rendering the system uncontrollable.

A further object of the invention is to provide an automatic end retarding mechanism independent of the main cylinder and 80 controlled by the counterweight, whereby the use of separate valves is obviated, and the system thereby rendered more safe and reliable.

The foregoing, and other objects and advantages, will be more fully explained in connection with the accompanying drawings, wherein

Figure 1 is an elevation of a system embodying the invention, Fig. 2 is a section 90 of the controlling valve, and Fig. 3 is an enlarged detail view showing the counterweight plunger at its lower position.

1 represents a main cylinder having a plunger 2 therein, and 3 is a car mounted on the upper end of the plunger. Connected to the car is a counterweight cable 4 running over an overhead sheave 5; thence around a movable sheave 6 and attached at the other end to the building at 7. The movable 100 sheave 6 is carried by a volute 8, which may also carry additional weights 9, and depend-

ing from the yoke 8 is an auxiliary plunger 10. The sheave 6, yoke 8 and plunger 10 will together comprise the counterweight, and preferably, in practice, will exceed the 5 weight of car 3 and plunger 2 by an amount equal to one-half the maximum load which the car is to carry, though it will be understood that the particular amount of excess weight on the counterbalance side, if any, 10 will not necessarily be this amount, and in some cases it may be desirable to have the weights on opposite sides balance each other more or less. 11 is a to-and-fro pipe leading to cylinder 1, and connected by a suitable 15 connection to a port 12 of the main three-position controlling valve 13.

In referring to the valve 13 as a three-position valve, I refer broadly to valves of the well-known three way type wherein 20 there is a central closed position and opposite extreme open positions, one extreme open position causing the car to go up and the other causing the car to go down, and the center closed position causing the car to 25 remain stationary, such valves being usually controlled from the car by a controlling lever having corresponding positions. It will, however, be understood that the actuating 30 connections for these three-position valves may be widely varied from that herein shown without departing from the invention.

14 is an auxiliary cylinder in part or wholly above the main cylinder 1, so as to 35 provide a head of water, or a water column for raising the plunger 2 and the car when the main valve is manipulated for this purpose. By reason of the movable sheave 6, and the cable connection 4 therewith, it will 40 be seen that the plunger 2 will move twice as fast as the plunger 10, and in order to avoid loss of pressure, the plunger 10 will have approximately twice the cross section of plunger 2, thereby making their volumes 45 equal. Whenever the plunger 2 goes up, plunger 10 will go down, and accordingly, the main valve 13 is connected by a pipe 15 with the cylinder 14, and the pistons and ports are so arranged that one movement of 50 the main valve permits such respective movements of the plungers to take place in both directions simultaneously. Inasmuch as the water column in cylinder 14 supplies lifting pressure for the car, and by reason of the 55 approximate balancing of the system, the car will ascend whenever cylinders 1 and 14 are connected, as the pressure required need be only sufficient to lift the live load. Where the car is overbalanced, the lifting pressure 60 will, of course, be less, in order to raise the car, and by making the excess weight equal to one-half the maximum live load, an operation will result well suited for average 65 operating conditions. By reason of the over-balancing of the car, the cylinder 14 be-

comes in effect, a loaded accumulator, and any live load the car descends with, reduces to a corresponding degree the amount of power required to lift the counterweight plunger.

The main valve comprises a stem 17 carrying pistons 18, 19, 20, 21, and has at one end a controlling passage 22, 27, which is connected with a pilot valve 23. This pilot valve is operated by manual connections upon the 70 car in a well known manner, these connections not being shown but being arranged to reciprocate lever 24. 25 is a link attached at one end to the lever 24, and at the other to the stem 26 of the pilot valve inside casing 75 23, which stem 26 carries suitable controlling pistons for admitting pressure to the lower side of piston 18 through pipes 22 and 27, to raise the main valve stem, thereby opening the main cylinder 1, through pipe 11, port 12 80 and port 28 of main valve 13 to the exhaust. Simultaneously, piston 21 connects supply port 29 of the main valve with port 30, and thence by pipe 15 to cylinder 14, thereby admitting pressure to cylinder 14. This operation causes the car to descend and the counterweight plunger 10 to ascend. To cause the car to ascend, the pipes 22 and 27 of the main valve, are, by a proper manipulation of the pilot valve stem 26, opened to 85 the exhaust, whereupon the supply pressure against the piston 21 will move the main valve stem downward so that piston 20 will uncover port 12, and thus establish a circulating passage between the cylinder 14 and 100 the cylinder 1, causing the car to ascend by the pressure in cylinder 14 as before stated. In this connection, it should be stated that the main valve stem is connected by a rack, gear and worm with the pilot valve stem 26, 105 so that the pilot valve being manually opened by the operator, will be automatically closed by the movement of the main valve. Also, the movement of the main valve will be proportional to the amount of throw given the 110 pilot valve.

A further feature of this invention comprises the automatic stop mechanism which is applied to the counterweight plunger and acting to automatically cushion and retard 115 the counterweight plunger at each end of its movement in cylinder 14. This forms a very effective mechanism for automatically stopping the car at the ends, since the pressures used in systems of this character are never sufficient to lift the car if it is entirely uncounterbalanced, so that if the counterweight cannot move it is immaterial whether the pressure be under the main plunger or not, as it cannot be sufficient to move the 120 car. On the other hand, if the movement of the counterweight plunger be cushioned and retarded at the top, by positive means, the car cannot go farther down even though 125 the exhaust of the main cylinder be open 130

and the pressure applied to lift the counterweight plunger. For cushioning the counterweight plunger 10 at the top, an auxiliary stopping or cushioning cylinder 33 is provided, and the lower end of plunger 10 is provided with an enlarged grooved portion 34 which will pass through a packing 35 and the water trapped above packing 35 will be forced out through the grooves 34. 5 As shown herein, these grooves are graduated lengths, so that as the plunger 10 moves up to the end of cylinder 33 the number of grooves through which the trapped water may escape is reduced, thereby increasing the cushioning effect as the end is reached. 10 In order to stop the car at the top and the plunger 10 at the bottom, the lower end of the plunger 10 is hollowed as at 36, and provided with a lower packing 37. At the end 15 of cylinder 14 is an upright perforated casting or tube 38 having graduated ports, of such a diameter as to pass within packing 37, whereupon the water thus trapped in the hollow end 36 is forced out through the graduated perforation as the plunger 10 approaches the bottom, thus cushioning its descent, and preventing the car from running over the top limit. These cushioning devices, depending upon the linear movement 20 of plunger 10, will be more effective, because the main plunger is moving at twice the linear speed of plunger 10, and no stresses are put on the main plunger 2, except those naturally due to the live load, and these will 25 not ordinarily be large or excessive because the system is either overweighted or balanced. 30

In order to prevent the formation of a vacuum at the top of cylinder 33, when the plunger 10 moves down, an auxiliary circulating passage 40 is provided between the opposite sides of packing 35, and this pipe 40 is controlled by a piston 41 on main valve stem 17 so that this passage 40 is opened at the center position of the main valve, and while it moves to connect the two cylinders through pipes 15 and 11, but when the main valve moves up from the center position to permit the car to descend and the counterweight plunger 10 to ascend, the piston 41 cuts off passage 40. 45

In the description thus far given of the operation, the design of the ports has not been particularly described, but it will be understood that the main valve ports will be so designed as to at times cause the main plunger to move quicker than the counterweight plunger and vice versa, which results can be accomplished by a proper design 50 of the ports so as to throttle the water supply at certain portions of the main valve stroke. For instance, in stopping the car going up, the escape of water from cylinder 14 should be throttled so as to retard the descent of the counterweight plunger 10, there-

by removing the pull of the counterweight plunger on the car and permitting the car to stop quicker by reason of gravity. In descending, if the admission of supply pressure to the cylinder 14 be throttled, the 70 counterweight plunger 10 will be retarded thereby putting a pull on the car and retarding it without increasing the strain on its plunger 2. Also the exhaust from the main cylinder could be throttled to secure a 75 similar retardation, but this would tend to buckle the plunger 2, if made too pronounced.

From the foregoing description, the nature and advantages of the invention will be 80 fully understood and it will be seen that a hydraulic elevator system is provided in which an economy of power will result, and also a material reduction in the compressing strains to which the plungers of underbalanced hydraulic systems are now subject. Furthermore, it will be seen that the car can be stopped going up within any limits which are practicable, and likewise in going 85 down. Also it will be seen that I have provided a controlling valve of novel and advantageous construction and simple in operation and design. By the use of the automatic end stopping mechanism described, the safety of the car will be insured without 90 involving any strains on its plunger, and also the use of extraneous valves, and connections operated by means of the car or devices in the elevator shaft is avoided. 95

Inasmuch as the invention is susceptible 100 of various modifications and changes in the form, proportions, design and arrangement of parts, it is not to be restricted to the precise form and arrangement herein shown and particularly described. 105

Furthermore, I wish to be understood that the power cylinders may be differently arranged, than as herein shown, in such manner as to be simultaneously controlled by a main valve, the plunger of one going 110 up while that of the other goes down.

Having thus described my invention, I declare that what I claim as new and desire to secure by Letters Patent, is,—

1. In an elevator system, the combination 115 with a car having a counterbalance heavier than the car, of separate hydraulic motors directly and independently connected to the car and the counterbalance, and a three-position valve for simultaneously controlling said motors, one of said motors in one position of said valve being directly connected with the other and supplying lifting power thereto.

2. In an elevator system, the combination 120 with a car having a counterbalance heavier than the car to an extent proportioned to the live load, of separate hydraulic motors directly and independently connected to the car and the counterbalance, said motors op- 125

- erating simultaneously in opposite directions, and a three-position valve for simultaneously controlling said motors, one of said motors in one position of said valve being directly connected with the other and supplying lifting power thereto. 5
3. In a hydraulic plunger elevator system, the combination with a hydraulic plunger supported car having a hydraulic plunger supported counterbalance directly connected thereto by overhead cables and heavier than the car, of separate motor cylinders carrying said respective plungers, said plungers operating simultaneously in opposite directions, 10 and a three-position valve for simultaneously controlling said motors, one of said motors in one position of said valve being directly connected with the other and supplying lifting power thereto. 15
- 20 4. In an elevator system, the combination with a car and a main plunger connected thereto, of a main cylinder therefor, a counterweight having a plunger, a cylinder for said counterweight plunger, the counterweight and plunger being heavier than the car and main plunger and located above the main cylinder, and a valve having two open positions, one connecting said cylinders and cutting off the pressure to raise the car, and 25 the other admitting supply pressure to the counterweight cylinder and opening the main cylinder to exhaust to lower the car. 30
5. In an elevator system, the combination with a hydraulic plunger carrying a car, of a heavier counterweight plunger, said plungers operating together in opposite directions in parallel cylinders, the counterweight cylinder being above the other cylinder, means for connecting said cylinders and 35 cutting off the pressure to raise the car, and means for lowering the car by admitting pressure to the counterweight cylinder and opening the other cylinder to exhaust. 40
- 45 6. In a hydraulic plunger elevator system, the combination with a main cylinder having a plunger carrying a car, of a counterweight comprising a second plunger heavier than the car and main plunger, a cylinder for said counterweight plunger located above said main cylinder and a controlling valve for connecting said cylinders and cutting off the pressure to raise the car, and opening the main cylinder to exhaust and the counterweight cylinder to pressure to 50 lower the car. 55
7. In a hydraulic plunger elevator system, the combination with a main cylinder having a plunger carrying a car, of a second cylinder located above the main cylinder, a 60 plunger in said latter cylinder connected to the car and main plunger to have one half the travel, said second plunger being heavier than the car and main plunger and of the same displacement as the main plunger, and
- a valve for connecting said cylinders and cutting off the pressure to raise the car, and opening the main cylinder to exhaust and the second cylinder to pressure to lower the car. 65
8. In a hydraulic plunger elevator system, the combination with a main cylinder having a plunger carrying a car, of a second cylinder located above the main cylinder, a plunger in said latter cylinder connected to the car and main plunger to have one half the travel, said second plunger being heavier than the car and main plunger and of the same displacement as the main plunger, a valve for controlling both plungers to raise and lower the car, and means in said second cylinder for automatically retarding the car at both ends. 70
9. In an elevator system, the combination with a hydraulic cylinder and a plunger carrying a car, of a counterweight comprising a second plunger, a cylinder therefor, and automatic end retarding mechanism for both ends controlled by said second plunger, substantially as described. 75
10. In an elevator system, the combination with a hydraulic cylinder and a plunger carrying a car, of a second cylinder and a plunger carrying a counterweight, and a hydraulic automatic end retarding mechanism for both ends independent of the said plunger and controlled by said counterweight, substantially as described. 80
11. In an elevator system, the combination with a hydraulic plunger carrying a car, of a counterweight carrying a plunger, said counterweight and plunger being heavier than the car and plunger, and automatic end retarding means for both ends controlled by said counterweight plunger, substantially as described. 85
12. In an elevator system, the combination with a main hydraulic plunger carrying a car, of a counterweight carrying a plunger, means for controlling the main plunger, and means carried by the counterweight plunger for automatically slowing the main plunger at the ends of travel of the counterweight plunger, substantially as described. 90
13. In an elevator system, the combination with a main hydraulic plunger carrying a car, of a counterweight carrying a plunger, means for controlling the main plunger, means carried by the counterweight plunger for automatically slowing the main plunger at the ends of travel of the counterweight plunger, and means for applying lifting power to the counterweight, substantially as described. 95
14. In an elevator system, the combination with a main hydraulic plunger carrying a car, of a counterweight heavier than the car comprising in part a plunger, hy- 100
- 105
- 110
- 115
- 120
- 125

draulic means preventing fall of the counterweight except when the main plunger is to be lifted, cylinders for said plungers, and means for connecting said cylinders and cutting off the pressure to lift the main plunger.

15. In an elevator system, the combination with a main hydraulic plunger carrying a car, of a counterweight and plunger exceeding the weight of the car and connected thereto by ropes, means for applying power from the counterweight cylinder to the main plunger to lift the car while the supply pressure is cut off, and for applying power to the counterweight plunger and opening the main cylinder to exhaust to lower the car, substantially as described.

16. In a hydraulic elevator system, the combination with a main hydraulic plunger and car, of a counterweight and plunger opposing the car and main plunger, and means for cushioning the counterweight plunger at the ends of its travel and thereby automatically retarding the car, substantially as described.

17. In an elevator system, the combination with a main cylinder, a plunger therein carrying a car, of a second cylinder carrying a plunger heavier than the car and main plunger, said plungers being connected by overhead ropes and sheaves causing the second plunger to move one half the travel of the main plunger, and three position valve mechanism for controlling said plungers simultaneously, said valve and its connections being arranged to cause the motor fluid to circulate directly from the second cylinder to the main cylinder in raising the car.

18. A hydraulic plunger elevator system comprising a hydraulic cylinder having a plunger carrying a car, a counterweight carrying a plunger working in a second cylinder, and automatic end retarding devices acting on said counterweight plunger for stopping the car at opposite ends of its travel, substantially as described.

19. The combination with a hydraulic cylinder containing a plunger, and a car mounted on said plunger, of a second cylinder containing a counterweight plunger connected with the car, means in said counterweight cylinder for automatically retarding the plunger at one end of the travel, a main valve, and means controlled by said main valve for permitting said counterweight plunger to start in the opposite direction, substantially as described.

20. The combination with a direct hydraulic plunger elevator, of a counterweight flexibly connected thereto, and means independent of the plunger and coöperating with the counterweight for automatically retarding the elevator at the ends.

21. The combination with a direct hy-

draulic plunger elevator, of a counterweight 65 flexibly connected thereto and moving with the car at a slower speed, and means independent of the plunger and coöperating with the counterweight for automatically retarding the elevator at the ends.

22. The combination with a direct hydraulic plunger elevator, of a counterweight plunger and hydraulic cylinder flexibly connected thereto, and hydraulic means coöperating with the counterweight plunger for 70 75 automatically retarding the elevator at the ends.

23. The combination with a direct hydraulic plunger elevator, of a counterweight plunger and hydraulic cylinder flexibly connected thereto and moving at a less speed, 80 and hydraulic means coöperating with the counterweight plunger for automatically retarding the elevator at the ends.

24. The combination with an elevator car, 85 of a hydraulic plunger having one end connected with the car, a cylinder containing said plunger, and means within the cylinder whereby the free end of said plunger is automatically retarded at each end of the 90 cylinder.

25. The combination with an elevator car, of a hydraulic plunger having one end connected with the car by means causing it to move at a less speed than the car, a cylinder 95 containing said plunger, and means within the cylinder whereby the free end of said plunger is automatically retarded at each end of the cylinder.

26. The combination with two cylinders 100 containing each a plunger, one cylinder supplying actuating pressure for the other to move the plungers in one direction, a controlling valve for said cylinders, and an auxiliary equalizing valve adapted to be 105 opened when said controlling valve is operated to connect the cylinders.

27. In an elevator system, the combination with a main hydraulic plunger carrying a car, of a counterweight connected therewith carrying a plunger, cylinders for said plungers, means for controlling the main plunger, and means carried by the counterweight plunger for automatically slowing both plungers at the ends of travel of the 115 counterweight plunger.

28. In a hydraulic plunger elevator system, the combination with a main cylinder having a plunger carrying a car, of a second cylinder located above the main cylinder, a 120 plunger in said latter cylinder connected to the car and main plunger to have one-half the travel, said second plunger being heavier than the car and main plunger and of the same displacement as the main plunger, and a single three-position valve for simultaneously connecting either motor to a source of power and the other to exhaust

- water therefrom to operate the car in both directions, said valve and its connections being arranged to cause the motor fluid to circulate directly from the second cylinder to the main cylinder in raising the car.
29. In an elevator system, the combination with a cylinder and a main hydraulic plunger carrying a car, of a counterweight heavier than the car comprising a second plunger, a hydraulic cylinder for said second plunger, and a single valve having separate passages for applying power to said second cylinder and simultaneously opening the main cylinder to exhaust to lower the car, and raising the car by opening the main cylinder to pressure and the counterweight cylinder to exhaust water therefrom, said valve and its connections being arranged to cause the motor fluid to circulate directly from the second cylinder to the main cylinder in raising the car.

30. In an elevator system, the combination with a main cylinder, a plunger therein carrying a car, of a second cylinder carrying a plunger heavier than the car and main plunger and of the same displacement, said plungers being connected by overhead ropes, and a three-position valve mechanism for simultaneously connecting either of said cylinders to exhaust water therefrom and the other to pressure to operate the car in both directions, said valve and its connections being arranged to cause the motor fluid to circulate directly from the second cylinder to the main cylinder in raising the car.

In testimony whereof I affix my signature, in presence of two witnesses.

KARL E. OSSIAN JANSSON.
